DESIGN FOR A LEVER

Harry Wolff, Lincoln, Nebr.

Application March 12, 1935, Serial No. 55,841

Term of patent 3½ years

To all whom it may concern:

Be it known that I, Harry Wolff, a citizen of the United States, residing at Lincoln, in the county of Lancaster and State of Nebraska, have invented a new, original, and ornamental Design for Levers, of which the following is a specification, reference being had to the accompanying drawing, forming part thereof.

Figure 1 is a view in front elevation of the lever.
Figure 2 is a view in rear elevation of the lever.
Figure 3 is a view in edge elevation of the lever.

I claim:

The ornamental design for a lever, as shown.

HARRY WOLFF.
